CLAIM

I claim the ornamental design for a knob for kitchen range, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a top perspective view of a knob for kitchen range; FIG. 2 is an end elevation view thereof, where the opposite end view is the same;

FIG. 3 is a side elevation view thereof, where the opposite side view is the same; and,

FIG. 4 is a top perspective view thereof.

Views not shown, including the underside of the knob in all figures, form no part of the claimed design. FIGS. 1-4 show the knobs using color photographs where the text and symbols bounded by the dash-dot lines form no part of the claimed design.
